chusetts

Application June 2, 1939, Serial No. 277,073

10 Claims. (Cl. 123—169)

The present invention relates to improvements in spark plugs, and particularly in spark plugs for high-compression airplane engines which are shielded to prevent radio interference.

5 Modern high-compression airplane engines operate at increasingly high temperatures, which puts increasingly severe demands on the spark plugs of such engines, and particularly on the insulating means serving to insulate the center electrode from the grounded spark plug shell. Thus the usual porcelain cores of automobile spark plugs, because of their susceptibility to cracking when subjected to wide-range temperature changes and the considerable decrease of the dielectric strength of porcelain at high temperatures, are unsuited for spark plugs of high-compression airplane motors, which as a rule now use mica insulation.

Such mica insulation consists of a spirally-wound mica ribbon, which forms a sleeve or "cigarette" disposed about the center electrode to insulate it from the shell, and of mica washers disposed perpendicularly to the central electrode and which provide mechanical and thermal protection of the sleeve against the scorching and corrosive action of the burning fuel. This construction, however, has shortcomings as satisfactory performance of the insulation depends on the gas-tightness of the washers, which tends to deteriorate in operation. As a result of this, corona discharge and sparkovers are likely to occur between the center electrode and the shell, particularly at "take-off" when the engine is cold and is operating at maximum cylinder pressure and at maximum spark-gap voltage.

Furthermore, mica itself has certain shortcomings in such use. For example, it is attacked by the combustion products of fuels comprising "anti-knock" compounds—now increasingly used—which results in its gradual disintegration in operation. Disintegration of mica is also likely to take place because the high temperature to which mica is subjected in operation is close to the critical temperature at which it gives up its water of crystallization.

Also, due to the low expansion coefficient of mica as compared with steel, the mica washers are liable to loosen.

A further drawback of present airplane spark-plug constructions and the use of mica insulators is that the heat is very poorly conducted away from the spark-plug tip, causing it to assume frequently temperatures of 700° to 850° C., bringing about its deterioration and also undesired preignition in the engine.

Such shortcomings of the present-day airplane spark plugs have proven to be a serious limiting factor which retards the development of airplane engines with still higher compression ratios.

To overcome the limitations imposed by mica insulators, it has been proposed to use in airplane spark plugs, insulators made of highly refractory metal oxides, such as aluminum-, magnesium-, or beryllium-oxide and similar in shape to the porcelain cores used for automobile spark plugs. Such cores can be made by artificially imparting to these oxides plasticity,—for example, pulverizing the oxide and mixing it with a preferably volatile plasticizer,—forming the plasticized oxides into the desired shape core and sintering the so-formed core.

Such sintered refractory oxides have a micro-crystalline structure devoid of any glassy phase and have various properties which are particularly useful for insulators in spark plugs. For example, their electrical resistance is not greatly affected with increasing temperatures, and cores made therewith have great mechanical strength, immunity to attack by ethyl leaded and other "anti-knock" compounded fuels and the combustion products of such fuels, non-porosity, and high thermal conductivity. Notwithstanding the enumerated desirable properties, sintered oxide insulators have found but scant application for spark plugs of airplane motors, and have been found unsuitable for shielded spark plugs of same. This is due to the fact that such cores, because of their good heat conductivity, carry a large portion of the heat developed in the combustion chamber to the upper portion of the spark plug, which heat if the spark plug is of the shielded type cannot be properly dissipated. As a result thereof the insulation of the high-voltage cable at the place where the cable is connected to the spark plug, rapidly chars and deteriorates causing short circuits and consequent misfiring of the engine.

It is therefore an object of my invention to provide a novel spark plug construction which permits full utilization of the advantages of highly refractory oxide cores without their disadvantages.

Another object of my invention is to provide a novel construction for spark plugs of the type shielded to prevent radio interference.

A further object of my invention is to provide novel means to dissipate the heat from spark plugs.

These and further objects of my invention will appear as the specification progresses.

In accordance with my invention, I provide around the central electrode of the spark plug an insulating core of a good heat-conducting and highly refractory material, and provide for a heat by-pass by means of which substantially all of the heat transmitted by the combustion gases to the lower portion of the core is passed to the grounded spark plug shell rather than being transferred through the core to the upper shielded portion of the spark plug. More specifically, I use a core of sintered aluminum-, magnesium-, or beryllium-oxide and of a shape similar to the porcelain cores used in automobile spark plugs, whereby in a cylindrical space formed between the core and the shell I provide a low melting point metal or alloy which is liquid at the temperature which it assumes in operation, and constitutes the above referred to heat by-pass from the core to the shell. Suitable materials for this purpose are lead, lead and tin alloys and in general metallic substances having a melting point which is below the minimum operating temperature of the portion of the core about which the heat by-pass is disposed.

In general, I prefer to lengthen the cylindrical middle portion of the core and also to increase the radial space between it and the shell beyond that customary in present day spark plugs.

By properly dimensioning the cross-sectional area of the liquid metallic by-pass, the temperature distribution in the spark plug can be accurately controlled and the heat which is transferred from the combustion chamber to the upper portion of the spark plug reduced to a negligible amount.

My invention will be further described with reference to the appended drawing forming part of the specification, and in which,

Figure 1 is a vertical section of a non-separable type radio-shielded spark plug made in accordance with my invention;

Fig. 2 is a diagram illustrating the general paths of the heat flow and heat dissipation in the spark plugs of my invention.

Referring to Fig. 1, the spark plug there shown has a metal shell 10 which comprises a hexagonal nut portion 11 having a bore 40 and a threaded portion 12 having a smaller bore 41, the portion 12 being adapted to be screwed into the combustion chamber of the engine (not shown). At the transition from the bore 40 to bore 41 a beveled shoulder 42 is formed.

Disposed within the shell 10 and upwardly extending therefrom is a core 16 of insulating material, preferably of sintered aluminum oxide or like highly refractory and good heat-conducting material.

The core 16 comprises a cylindrical middle portion 43 and a lower and an upper tapered portion 49 and 47 respectively, the portion 47 extending into a cylindrical portion 48 which projects beyond the shell 10.

The central portion 43 of insulator 16 has a smaller diameter than has the bore 40, this resulting in an annular space 19 between the shell 10 and the portion 43.

At their junction with portion 43 the tapered portions 47 and 49 are rounded as shown at 50 and 51. Against the shoulders 50 and 51, press annular conical gaskets 11 and 18 made of suitable material, such as soft electrolytic copper, which firmly position the core 16. The lower gasket 18 thereby presses with its bottom face against the shoulder 42, whereas the upper

gasket with its top face presses against shoulder 44 of the shield 13 later to be described. The gaskets 11 and 18 serve as mechanical protection for the core 16 as well as a gas seal, and also assist in the transmission of the heat from the core 16 to the shell 10.

Disposed within an axial bore 52 of core 16 is a rod 21 of suitable metal, such as pure nickel, the lower end of which carries a frustoconical shaped sparking tip 22 abutting with its base against the end face of tapered core portion 49. The tip 22 is made of a metal which is highly resistant to corrosion at high temperatures, for example, of stainless steel. The tip 22 is secured to the rod 21, preferably by welding, so as to provide for a good heat conducting joint between the two, such welding preferably to take place in a reducing atmosphere, for example, in hydrogen.

To prevent longitudinal displacement of the rod 21 within the core 16, an insert 23 is embedded in the core extension 48 and threadedly engages the free end of the rod 21.

To insure a gas-tight fit of the rod 21 in the core 16 it is, before its assembly with the core, coated with a high-temperature-resistant ceramic cement 53.

Instead of providing a separate insert embedded in the core 16, the rod 21 itself may be cast in the axial bore 52.

The second sparking electrode 24 is disposed in the slightly enlarged lower end 54 of bore 41, and consists of a non-corrosive refractory metal or alloy for instance of nickel-barium alloy. Electrode 24 is press-fitted within the bore 54, and to insure its perfect thermal contact with shell portion 12, it is preferably hydrogen-brazed thereto. The electrode 24 may be of the conventional four-prong type whereby through proper shaping of its prongs and their proper spacing relative to the sparking tip 22, such troubles as may arise from capillary collection of oil or water are minimized and the sparking surfaces can be easily cleaned by a sandblast.

To shield the spark plug from causing radio interference, I surround the upper portion of the core 16 with a tubular shield 13 which extends into the bore 40 of the shield 10, and as already stated abuts with its lower shouldered end 44 against the upper sealing gasket 17. To secure the shield 13 to the shell 10, the free end of the shell is crimped as shown at 14. Interposed between the crimp 14 and the shoulder 44 is a metal sleeve 15 which presses against shoulder 44 and also serves to improve heat transfer from the shield 13 to the shell 10. Sleeve 15 is made of a good heat-conducting metal, such as copper.

The cable connector, which connects a high-tension armored cable 25 to the spark plug, comprises an elbow 28 provided at its free end with a threaded gland socket 26 in which is disposed a soft lead tapered sleeve 27. The other end of the elbow 28 is secured to the shield 13 by means of a flanged sleeve 37 coupled with an internally-threaded socket 29, the latter engaging a threaded extension 38 of the shield 13.

The cable connector and cable terminal portion of the spark plug are so designed and dimensioned as to permit free interchangeability of the spark plug of my invention with standard spark plugs.

Disposed within the shield 13 and extending from its bottom shoulder 44 to its top shoulder 55 is a cylindrical mica liner 34 formed of a

spirally-wound strip of mica. Within the upper portion of the liner 34 and abutting against shoulder 55 is a collar 31 which in its turn surrounds a sleeve 30, the latter extending into

5 and beyond the threaded extension 38 of shield 13. Sleeve 30 and collar 31 are preferably of linen-base laminated "Bakelite" and are secured to each other and to the liner 34 by means of a "Bakelite" cement or other suitable binder.

10 Disposed within the lower end of the sleeve 30 is a conical brass cup 32 provided with a downward-extending tubular portion 56 into which are secured the strands of the cable 25. Electrical connection between the cup 32 and the center rod 21 is made by means of a conical coil spring 33 which surrounds the extension 56 and is compressedly disposed between the cup 32 and the flat enlarged head 57 of the insert 23.

The mica liner 34, which covers the entire 20 exposed inner surface of the shield 13, prevents corona discharge and flashovers between the shield 13 and the contact spring 33, respectively the exposed top 57 of insert 23.

To divert the heat flow and prevent the heat 25 from passing from the lower portion of the spark plug to its upper portion via the core 16, I provide in accordance with the invention, in parallel to the central portion 43 of the core 16, a low-resistant heat path. For this purpose I 30 provide in the annular space 19 a low melting-point metal or alloy 35, for example, lead, or a lead-tin alloy which is liquid at the temperature which it assumes in the normal operation of the spark plug.

35 Low melting point metals other than the above are also suitable for the purposes of the invention, for example, mercury. However, in this case the gaskets 17 and 18 are required to be of a metal which does not form an amalgam 40 with mercury for example, of "dead soft" steel or the like.

To permit heat expansion of liquid metal 35, I provide for an expansion space 39 on top thereof. In general, I prefer to give the central 45 portion 43 a greater length and to the space 19 a greater radial width than that found in standard spark plugs, to thereby increase the effect of the low heat-resistant by-pass. I have found that this by-pass permits substantially accurate 50 predetermination of the temperature at the various points of the spark plug, and that its proper dimensioning makes it possible to pass through the by-pass to the shell 10 practically all of the heat absorbed by the lower portion 55 of core 16, thereby maintaining the upper portion of the spark plug substantially at a temperature, well below the charring temperature of the cable insulation.

To insure a gas tight seal between the spark 60 plug and the cylinder head there is disposed between the two a copper gasket 36 which also facilitates heat transfer from the shell 10 to the cylinder head (not shown). To increase this heat flow, I prefer to use a solid copper gasket.

65 Referring to the heat flow diagram (Fig. 2) in which the curved arrows indicate the paths of heat flow, it should be noted that the surface temperature of that part of the core 16 which is exposed to the combustion gases is substantially uniform and that all of the heat absorbed by the core portion 49 and the tip 22 passes upwardly. One portion of this heat without reaching the center portion 43 passes to the shell 10 through the gasket 18. However, the major 70 portion of the heat reaches the center portion

43 and is mainly dissipated through the heat by-pass, i. e., through the metallic liquid 35 to the shell 10. Such heat as may remain absorbed in the core will pass to the shell through gasket 17 and the heat flow which reaches the upper 5 portion of the spark plug is negligible.

The heat transferred from the spark plug core to the shell 10 is given up directly to the surrounding air and through the gasket 36 to the cylinder head 58 of the engine.

10

The spark plug described hereabove is of the non-separable type. My invention is equally applicable to "separable" types of spark plugs, in which case the shield and the shell instead of being fixedly connected, are threadedly engaged 15 with each other. This permits disassembling of the spark plug for cleaning and adjustment.

My invention is also usable for the so-called "short-reach" type of spark plug, in which case the lower tapered portion of the core and the 20 threaded portion of the shell are correspondingly shortened.

25 Thus while I have described my invention in connection with a specific example, I do not wish to be limited thereto as obvious modifications thereof will occur to those skilled in the art.

What I claim is:

1. A spark plug comprising a shell of conducting material, a center electrode and a second electrode, an insulator disposed between the 30 shell and the center electrode, and means to improve the heat transfer from the insulator to the shell, said means comprising a metallic fluid disposed between said insulator and said shell.

2. A spark plug comprising a metal shell, an 35 insulating core positioned within said shell, a center electrode supported by said insulator, a second electrode, and means to facilitate heat flow from the core to the shell, said means comprising a metallic fluid disposed between said 40 core and said shell.

3. In a spark plug comprising a shell of conducting material, a center electrode and an insulator of highly heat-conductive material disposed between said shell and said electrode, 45 means to improve the heat transfer from the insulator to said shell, said means comprising a metal of low melting temperature disposed between said insulator and said shell.

4. In a spark plug comprising a shell of 50 conducting material, a center electrode, an insulator having a micro-crystalline structure devoid of any glassy phase concentrically positioned within said shell around said electrode, means to facilitate the transfer of heat from said insulator, said means comprising a metal of low melting temperature disposed between said insulator and said shell.

5. In a spark plug, a metal shell, and a central electrode, and two concentrical sleeves disposed 60 between the electrode and the shell, one of said sleeves being of an insulating material and the other consisting of a metal which liquefies at the temperature it assumes in the operation of the spark plug.

6. A spark plug for high-duty airplane engines comprising a metal shell, a grounded electrode attached to said shell, an insulator spacially disposed in said shell, a center electrode disposed in said insulator and two spaced gaskets 70 positioning said insulator in said shell, and a heat conducting filling within the space formed between the shell, the insulator and the gaskets to increase the rate of heat flow from the insulator to the shell.

7. In combination, a spark plug comprising a shell of conducting material, a center electrode and another electrode, an insulator disposed between the center electrode and shell and spaced from said shell, an insulated high-tension conductor, terminal means for connecting said conductor to said center electrode, and means to prevent the heat transfer from said insulator to said conductor, said means comprising a fluid heat-conducting path within said shell.
8. In a radio shielded spark plug having a lower and an upper portion, a shell enclosing said lower portion and a shield enclosing said upper portion, and means to divert the heat absorbed by the lower portion from reaching the upper portion, said means comprising a low-resistance heat-conducting path within said lower portion formed by a metallic fluid disposed within said shell.
9. A spark plug comprising a metal shell, a

center electrode and a grounded electrode, a one-piece insulator disposed around said center electrode, an upward-extending metallic sleeve surrounding the upper portion of said insulator, and a low-melting temperature metal mass disposed within said shell around the lower portion of said insulator. 5

10. A spark plug comprising a shell of conducting material, a center electrode, a second electrode, an insulator spacially positioned within said shell, an upper and a lower gasket spacially separated and disposed about the middle portion of said insulator, and a heat-conducting filling within the space formed between the insulator, the shell and the two gaskets respectively to substantially prevent the heat flow in the insulator from reaching its portion extending above the upper gasket. 10 15
